[57] CLAIM

I claim the ornamental design for a thin-walled container, as shown and described.

DESCRIPTION

FIG. 1 is a front view of a thin walled container showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof; and,

FIG. 7 is a perspective view thereof, in an open position.
